Des. 1085

William Loyd, of Philadelphia, Pa.
Letters Patent No: 1085. dated Feby 22, 1859.

The Schedule referred to in these Letters Patent and making part of the same.

To all whom it may concern;

Be it known that I, William Loyd, of the City of Philadelphia
and State of Pennsylvania, have invented or produced a new and improved Design for a

D

Wes. 1085

Stereoscope Case, and I do hereby declare the following to be a full and exact description thereof reference being had to the accompanying drawing which is a perspective view of my new Stereoscope Case.

I make the case A, in the form of a book as shown, placing the lenses in the back at B. B. The upper leaf C. I make with a hinge, and use its under-surface as a reflector to throw the light down upon the Picture.

The slides D. are held in grooves a. a. in the usual way. By making the front of the book of ground glass the case is adapted to the inspection of transparent pictures, the reflector C. being closed.

An instrument made in this form is an appropriate and elegant ornament for the drawing room table.

What I claim as a new and ornamental design is making a Stereoscope base in the form of a book as described and shown.

The above specification signed & witnessed this 1st. day of Jan-

uary. A. D. 1859.
